UNITED STATES PATENT OFFICE.

THOMAS E. STURTEVANT, OF DOVER, NEW JERSEY, ASSIGNOR TO MCKIERNAN-TERRY DRILL COMPANY, OF DOVER, NEW JERSEY, A CORPORATION OF NEW JERSEY.

SUBAQUEOUS PILE-HAMMER.

1,257,762.

Specification of Letters Patent. Patented Feb. 26, 1918.

Application filed April 17, 1917. Serial No. 162,697

To all whom it may concern:

Be it known that I, THOMAS E. STURTEVANT, a citizen of the United States, and a resident of Dover, Morris county, and State 5 of New Jersey, have invented certain new and useful Improvements in Subaqueous Pile-Hammers, of which the following is a specification, reference being had to the accompanying drawings, forming a part 10 thereof.

My invention relates to improvements in pile hammers and more particularly to a structure which is capable of being operated under water. Its object is to provide a simple, rugged and efficient apparatus for driving piles and the like and to so construct the parts that submerging it under water will not affect its effectiveness.

In order that my invention may be thoroughly understood I will now proceed to describe the same in the following specification, and then point out the novel features thereof in appended claims.

Referring to the drawings:

Figure 1 is a sectional side elevation of a pile hammer made according to and embodying my invention, the section being taken through the center of the apparatus.

Fig. 2 is a sectional front elevation of the same structure, the section being taken on the line 2—2 of Fig. 1, looking in the direction of the arrows.

Fig. 3 is an elevation of a portion of the valve rod and

Figs. 4, 5 and 6 are sectional plan views of the rod, the sections being taken respectively on the lines 4—4, 5—5 and 6—6 of Fig. 3.

Figs. 7, 8 and 9 are sectional plan views of the apparatus shown in the preceding figures, the sections being taken respectively on the lines 7—7, 8—8 and 9—9 of Fig. 1.

Fig. 10 is a sectional side elevation of a simple apparatus which also embodies this invention.

Fig. 11 is a sectional plan view of the structure shown in Fig. 10.

Like characters of reference designate corresponding parts in all the figures.

10 is a prismatic body of substantially square cross-section, having a central bore 11 which forms an engine cylinder. 12 is a piston which reciprocates in this cylinder,

and 13 is its piston rod. The lower end 14 of this body forms the lower cylinder head through which the piston rod extends, and 15 is a stuffing box of ordinary construction. 16 is the upper cylinder head on which is rotatively supported a sheave 17 by brackets 18.

20 is a hammer guide barrel of the same form in cross-section as the body 10. This has a central bore 21 of larger diameter than the cylinder 11, in which is a hammer block 22 which is affixed to the piston rod 23 and arranged to be reciprocated by the piston 12. Longitudinal grooves 24 are cut in the bore 21.

At the lower end of the barrel 20 is a head 24 with a bore 25 of substantially the same diameter as that of the bore 21 and an upper bore 26 of smaller diameter. Within this head is an anvil block 27 which fits the bore 25 and has packing rings 28. This anvil block has an upper portion 29 which projects into the bore 26 and a lower portion 30. 31 is an end member which fits around the part 30 of the anvil block and over the lower end of the head 24.

The cylinder head 16, body 10, the barrel 20, head 24 and end member 31 are held together by through bolts 32 on the ends of which are nuts 33.

In the body 10 are three vertical bores, the center one of which designated by 40 is a valve cylinder. The one designated by 41 is an air passage in communication with an inlet port 42. The other bore 43 forms a passage connected with exhaust port 44. 45 is a passage between the upper end of the main cylinder 11 and the upper part of the valve cylinder. 46 is a similar passage between the lower end of cylinder 11 and the lower part of the valve cylinder 40.

The valve rod 50 fits in cylinder 40. Opposite port 45 it is cut away as at 51—52 so that when in the position shown in Fig. 7, the cut away portion 52 affords a connecting passage from the upper end of cylinder 11 through port 45 with passage 43 and thus 100 to exhaust. The valve rod is cut away opposite port 46 as at 53 so that when in the position shown in Fig. 8, it connects the lower end of cylinder 11 with the intake or supply.

When the valve rod is rotated 90° in an

anti-clockwise direction these conditions will be reversed and the upper end of the cylinder 11 will be connected through the cut away part 51 of the valve rod with the supply and its lower end with the exhaust.

10 The valve rod extends to and is seated in the head 24 at 54. The hammer block 22 has a longitudinal groove 55 cut in one side into which the valve rod fits, thus holding the hammer block against rotation. There is however, a short rib 56 projecting integrally from the hammer block into the groove 55 and into a groove 57 in the valve rod, the ends of which are inclined 15 in opposite directions. By this arrangement an oscillatory rotation is imparted to the valve rod by the hammer block during its movement which causes the ports previously described to be opened and closed 20 to actuate the piston.

25 37 is a port with which an air tube 38 may be connected through which air from a suitable source of supply may be led through a regulating valve 39. It is to be understood that suitable tubes may be connected similarly with the supply and exhaust ports 42 and 43.

30 The operation of this device is as follows:—the apparatus is supported by a cable or chain run under sheave 17. It is lowered onto the object to be driven with the lower end 30 of the anvil block 27 resting upon the object so that substantially the whole weight of the apparatus is upon 35 the pile or other object to be driven. Now when motive fluid under pressure is admitted through port 42 it will be led alternately through the rotary valve to the opposite ends of the cylinder 11. If it is led first 40 to the lower end thereof, the piston 12 will be raised and with it the hammer block 22. During this part of the operation the upper end of the cylinder will be connected through the valve with exhaust.

45 This movement of the hammer block will turn the valve and put it in position to connect the upper end of the cylinder 11 with the air supply and the lower end thereof with exhaust. This will result in the downward movement of the hammer block which will deliver a heavy blow on the anvil block 27 at the end of its stroke, and as the latter is resting on a pile or something else to be driven, the blow will be transmitted to the 50 latter object. It is evident that this operation will be repeated rapidly and continuously as long as motive fluid such as compressed air, is supplied.

55 The construction of the device is such 60 that it is water-tight so that when it is submerged its operation will not be retarded thereby. The result is that a pile for example may be driven down under the water level as far as desired.

The air supply to the hammer block guide 65 barrel through tube 38 is provided so that the packing rings 28 need not be depended upon to keep the water out of the apparatus. Air is supplied through the regulating valve 39 at a desired pressure sufficient to counter-act the pressure of the water due to the depth of submersion of the device. The slots or grooves 23 provide paths for free circulation of the air between opposite ends of the hammer block.

70 The device shown in Figs. 10 and 11 is a simple structure which also embodies my invention. In this structure 60 is a prismatic body having a central bore 61 in which is a hammer block 62. 63 is the upper head of this device and 64 its lower head. Below this is a cupped end member 65. These parts are held together by through bolts 66 on the ends of which are nuts 67. 68 are vertical guide channels on opposite sides of the body 80 60, and 69 is a stuffing box in the upper head 63.

75 A rod 70 is affixed to the hammer block 62. This extends through the stuffing box 69 and at its upper end is an eye 71. 72 is a port leading into cylinder 61 and 73 is a pipe or tube through which air under pressure may be admitted through a regulating valve 74 to the cylinder. The cylinder is cut away as at 75 to give free access of this air 85 to each end of the hammer block.

80 In the lower head 64 is an anvil block 80 provided with packing rings 81. Its upper end 82 is of smaller diameter than is the part which carries the packing rings and projects 100 into a restricted opening in the head 64. The lower end of the hammer block is also restricted in diameter as at 83 to allow it to pass freely into the smaller bore of head 64. The lower end 84 of the anvil block is 105 also of smaller diameter than that of the central part of this member and an annular collar 85 of the cupped member fits around this lower end of the anvil block and retains it in place.

110 The apparatus shown in Figs. 10 and 11 works on the same principle as does that shown in the preceding figures, so far as the driving and the means for keeping water out of the hammer block chamber is concerned. This apparatus, however, has no engine and the reciprocation of the hammer block is to be accomplished by some outside agency.

115 The device is designed to be used with an ordinary pile driver. It is placed between the pile driver guides, the channel 68 being arranged to fit such guides. It is then lowered onto a pile, the cupped member 65 fitting over the upper end thereof.

120 Now the pile driver engine is connected by a rope or cable with eye 71 and the hammer block reciprocated thereby.

I have illustrated and described two mechanisms which embody this invention but do not mean to limit myself to these or any other specific designs of structure but intend 5 no limitations other than those imposed by the appended claims.

What I claim is:

1. A casing constructed to form an elongated chamber, a reciprocatory hammer block therein, an actuating rod affixed to the hammer block and extending above said chamber, an upper head having a water-tight bearing for the rod, and arranged to close the upper end of the hammer block chamber, a lower head at the other end of the chamber, an anvil block slidably fitted in said lower head closing the lower end of said chamber and means for supporting the anvil block in said lower head. 10
2. A casing constructed to form an elongated chamber, a reciprocatory hammer block therein, a portion of the inner walls of said casing forming guides for the hammer block, an actuating rod affixed to the hammer block and extending above said chamber, an upper head, having a water-tight bearing for the rod, said head being arranged to close the upper end of the hammer block chamber, a lower head at the other 15 end of the chamber, having a cylindrical bore, an anvil block slidably fitted therein closing the lower end of said chamber and means for supporting the anvil block in said lower head. 20
3. A casing constructed to form an elongated chamber, a reciprocatory hammer block therein, a portion of the inner walls of said casing forming guides for the hammer block, an actuating rod affixed to the hammer block and extending above said chamber, an upper head, having a water-tight bearing for the rod, said head being arranged to close the upper end of the hammer block chamber, a lower head at the other 25 end of the chamber, having an annular collar and a cylindrical bore, an anvil block having a cylindrical body portion of less length than that of the bore in said lower head fitted in said bore and having end portions 30 of smaller diameter, the upper end portion of said anvil block projecting into said annular collar, and an end member surrounding the lower end portion of the anvil block adapted to fit over the end of a pile. 35
4. A prismatic body having a cylindrical bore forming an elongated chamber, a cylindrical reciprocatory hammer block therein, the walls of said bore being cut away longitudinally to provide for free circulation of air from one end of the hammer block to the other, an actuating rod affixed to the hammer block and extending above said chamber, an upper head, having a water-tight bearing for the rod, said head being ar- 40
5. A casing constructed to form an elongated chamber, a reciprocatory hammer block therein, an actuating rod affixed to the hammer block and extending above said chamber, an upper head having a water-tight bearing for the rod, and arranged to close the upper end of the hammer block chamber, a lower head at the other end of the chamber, an anvil block slidably supported in said lower head closing the lower 45 end of said chamber, and means for supporting the anvil block in said lower head, and means for admitting air under pressure to the hammer block chamber. 50
6. A casing constructed to form an elongated chamber, a reciprocatory hammer block therein, the inner walls of said casing forming guides for the hammer block, an actuating rod affixed to the hammer block and extending above said chamber, an upper head, a stuffing box therein forming a water-tight bearing for the rod, said head being arranged to close the upper end of the hammer block chamber, a lower head at the other end of the chamber, having an annular collar and a cylindrical bore, an anvil block having a cylindrical body portion of less length than that of the bore in said lower head fitted in said bore and having end portions of smaller diameter, the upper end portion of said anvil block projecting into said annular collar, an end member surrounding the lower end portion of the anvil block adapted to fit over the end of a pile, and means for admitting air under a desired pressure to the hammer block claim- 60 ber. 65
7. A prismatic body having a cylindrical bore forming an elongated chamber, a cylindrical reciprocatory hammer block therein, the walls of said bore being cut away longitudinally to provide for free circulation of air from one end of the hammer block to the other, an actuating rod affixed to the ham- 70

mer block and extending over said chamber, an upper head, a stuffing box therein forming a water-tight joint for the rod, said head being arranged to close the upper end 5 of the hammer block chamber, a lower head at the other end of said chamber having an annular collar and a cylindrical bore, an anvil block having a cylindrical body portion of less length than that of the bore in said 10 lower head, fitted in said bore, a packing ring in said cylindrical body portion, said anvil block also having end portions of smaller diameter, the upper end portion of the anvil block projecting into said annular 15 collar, an end member, surrounding the lower end portion of the anvil block and adapted to fit over the end of a pile, said upper and lower heads and end member having the same external shape in cross section as 20 that of the prismatic body, and through bolts near the corners of said parts for tying the upper head, the body, the lower head and the end member together, an air supply pipe connected with the hammer block 25 chamber, and a regulating valve in said pipe.

8. A casing constructed to form an elongated chamber, a reciprocatory hammer block therein, the inner walls of said casing forming guides for the hammer block, an 30 actuating rod affixed to the hammer block and extending above said chamber, an upper head, a stuffing box therein, said head being arranged to close the upper end of the hammer block chamber, a lower head at the 35 other end of the chamber, having a cylindrical bore, an anvil block slidably fitted therein closing the lower end of said chamber, an engine cylinder in said upper head, a piston in said engine cylinder connected with the 40 actuating rod, and fluid pressure means for actuating said piston.

9. A casing constructed to form an elongated chamber, a reciprocatory hammer block therein, the inner walls of said casing forming guides for the hammer block, an actuating rod affixed to the hammer block and extending above said chamber, an upper head, a stuffing box therein, said head being arranged to close the upper end of the 45 hammer block chamber, a lower head at the other end of the chamber, having an annular collar and a cylindrical bore, an anvil block having a cylindrical body portion of less length than that of the bore in said lower head fitted in said bore and having end portions of smaller diameter, the upper end portion of said anvil block 50 projecting into said annular collar, an end member surrounding the lower end portion 55 of the anvil block adapted to fit over the end of a pile, means for admitting air under a desired pressure to the hammer block chamber, an engine cylinder in said upper head, a piston in said cylinder con-

nected with the actuating rod, and fluid pressure means for actuating said piston.

10. A prismatic body having a cylindrical bore forming an elongated chamber, a cylindrical reciprocatory hammer block therein, the walls of said bore being cut away longitudinally to provide for free circulation of air from one end of the hammer block to the other, an actuating rod affixed to the hammer block and extending above said chamber, an upper head, a stuffing box therein, said head being arranged to close the upper end of the hammer block chamber, a lower head at the other end of said chamber having an annular collar and a cylindrical bore, an anvil block having a 70 cylindrical bore, an anvil block having a cylindrical body portion of less length than that of the bore in said lower head, fitted in said bore, a packing ring in said cylindrical body portion, said anvil block also 75 having end portions of smaller diameter, the upper end portion of the anvil block projecting into said annular collar, an end member, surrounding the lower end portion of the anvil block and adapted to fit over 80 the end of a pile, said upper and lower heads and end member having the same external shape in cross-section as that of the prismatic body, through bolts near the 85 corners of said parts for tying the upper head, the body, the lower head and the end member together, an engine cylinder connected with the actuating rod, and fluid pressure means for actuating said piston.

11. A prismatic body having a cylindrical bore forming an elongated chamber, a cylindrical reciprocatory hammer block therein, the walls of said bore being cut away longitudinally to provide for free circulation of air from one end of the hammer block to 105 the other, an actuating rod affixed to the hammer block and extending above said chamber, an upper head, a stuffing box therein, said head being arranged to close the upper end of the hammer block chamber, a lower head at the other end of said chamber having an annular collar and a cylindrical bore, an anvil block having a 110 cylindrical body portion of less length than that of the bore in said lower head, fitted in 115 said bore, a packing ring in said cylindrical body portion, said anvil block also having end portions of smaller diameter, the upper end portion of the anvil block projecting into said annular collar, an end 120 member surrounding the lower end portion of the anvil block and adapted to fit over the end of a pile, said upper and lower heads and end member having the same external shape in cross section as that of the 125 prismatic body, through bolts near the corners of said parts for tying the upper head, the body, the lower head and the end

member together, an air supply pipe connected with the hammer block chamber, a regulating valve in said pipe, an engine cylinder in said upper head in alinement 5 with the hammer block chamber, a piston in said engine cylinder connected with the actuating rod, an oscillatory valve at one side of said engine cylinder, said rod ex-

tending down to and being seated in said lower head, and means for causing the re- 10 ciprocations of the hammer block to oscillate said valve.

In witness whereof, I have hereunto set my hand this 13 day of April, 1917.

THOMAS E. STURTEVANT.
